UNITED STATES PATENT OFFICE.

CHRISTOPHER C. BOYKIN, OF NORFOLK, VIRGINIA.

DESIGN FOR A SOUVENIR CRADLE.

No. 87,768.

Specification for Design.

Patented Jan. 2, 1906.

Application filed October 17, 1905. Serial No. 283,186. Term of patent 3½ years.

To all whom it may concern:

Be it known that I, CHRISTOPHER C. BOYKIN, a citizen of the United States, residing at Norfolk, in the county of Norfolk and State of Virginia, have invented a new, original, and ornamental Design for a Souvenir Cradle, of which the following is a specification, reference being had to the accompanying drawings, forming a part thereof.

The figures are perspective views of a souvenir cradle, showing my new design.

I claim—

The ornamental design for a souvenir cradle, as shown.

CHRISTOPHER C. BOYKIN.
